UNITED STATES PATENT OFFICE.

BRUCE C. WHITE, OF NEW YORK, N. Y., ASSIGNOR TO R. HOE AND CO., OF NEW YORK,
N. Y., A CORPORATION OF NEW YORK.

HYDRAULIC PRESS.

1,241,691.

Specification of Letters Patent.

Patented Oct. 2, 1917.

Application filed July 13, 1915. Serial No. 39,540.

To all whom it may concern:

Be it known that I, BRUCE C. WHITE, a citizen of the United States, residing at New York city, county of New York, and State 5 of New York, have invented certain new and useful Improvements in Hydraulic Presses, fully described and represented in the following specification and the accompanying drawings, forming a part of the same.

10 This invention relates particularly to hydraulic presses of that type in which the pressure fluid is forced into the press by pumps, and in which a plurality of plungers of different sizes are used successively, one 15 for low pressure and high speed in the first pressing movement, and the other for high pressure and low speed in the latter part of the pressing movement.

The special object of the invention is to 20 provide a simple, efficient and durable construction of such apparatus, in which the change from low to high pressure is made automatically, and in which convenient means are provided for holding the plunger 25 under pressure and relieving the pressure for the return of the plunger.

In addition to means for securing the 30 above general results, the invention includes various features of construction and combinations of parts, as fully described hereinafter and specifically pointed out in the claims.

For a full understanding of the invention, a detailed description of a construction embodying the same will now be given in connection with the accompanying drawings forming a part of this specification, which 35 illustrate one of the preferred embodiments of the invention.

In the drawings—

40 Figure 1 is a sectional elevation of the apparatus, the section being taken centrally through the press plunger;

Fig. 2 is a sectional plan, with the press plunger removed and the pump driving pulley partly broken away to show the clutch;

Fig. 3 is a sectional plan through the pump case or reservoir, on the line 3—3 of Fig. 4;

Fig. 4 is a cross section on the line 4—4 of Fig. 3;

50 Fig. 5 is a section on the line 5—5 of Figs. 3 and 4;

Fig. 6 is a section on the line 6—6 of Figs. 3 and 5;

Fig. 7 is an enlarged detail section of the automatic control valve and ports shown in 55 Figs. 5 and 6;

Fig. 8 is an enlarged plan of the cross-heads and connections, and

Fig. 9 is a section on the line 9—9 of 60 Fig. 8.

Referring to the drawings, A is the hydraulic chamber or cylinder in which moves the main press plunger B, and C the small cylinder in which moves the low pressure plunger D connected to the bottom of the 65 main or high pressure plunger B. E is a fixed abutment coacting with main press plunger B. Cylinders A, C are supplied with oil or other suitable liquid through, respectively, pipes 10, 11, through which the 70 liquid is forced from pump case and reservoir F by pumps, hereafter described. An air tap 12, for drawing off any air that may collect above the liquid in cylinder A is preferably provided, and a sealing groove 13 75 in plunger B preferably used, to seal cylinder A against the entrance of air past the plunger, this sealing groove 13 being supplied with sealing liquid by pipe 14 connecting with liquid tank 15, supplied in any 80 manner, and provided with overflow pipe 16 for overflow to the pump case or reservoir F.

Referring now to the liquid supply apparatus within the reservoir F, there are provided one or more pumps, preferably a plurality, and three being shown, these pumps being driven from eccentric shaft 17 which is driven by gears 18, 19 from power shaft 20, shown as driven by pulley 21 through clutch 22, the movable clutch member being carried 90 by a sleeve 23 and moved for clutching and unclutching shaft 20 by a cam sleeve 24 having cam groove 1, as shown clearly in Figs. 2 and 3, cam sleeve 24 being carried by shaft 25 which extends through the pump case, F 95 and is operated by hand lever 26 outside of the opposite end of the pump case, this shaft 25 acting also to control pressure valves, described hereinafter.

Upon the eccentric shaft 17 are mounted 100 the eccentric sleeves 27 carrying the forked eccentric rods 28, the forks of each rod embracing the cross-head block 29 sliding in top and bottom cross-head guides 30, the forks 28 being secured to pins 31 passing 105 through the cross-head blocks 29 and free to

turn therein. The bottom and top cross-head guides 30 are formed respectively on a bottom plate 32 mounted in the case in a suitable manner, and on a cover 33 removable from plate 32 and shown as bolted to the latter, so that the cross-heads and forked ends of the eccentric rods are readily accessible and removable by taking off the cover 33 carrying the top cross-head guides 30. It will be seen also that each of the forked eccentric rods with its cross-head 29 and pin 31 forms a complete unit, and that the outer ends of the eccentric rods bear against and form side bearings for each other, with the two outside eccentric rods bearing against the inner side of cover 33, so that no intermediate fixed side bearings between the eccentrics are required, and a very compact and efficient construction thus secured. Each of the cross-heads 29 forms the head or stem of a single-acting pump plunger *a* moving in small cylinder *b* connected with pulsation chamber *c* having a suction port connecting with the reservoir inside case F and controlled by suction valve *d*, and a discharge port connecting with discharge chamber *e* and controlled by discharge valve *f*. The valves *d*, *f* are shown as being formed with spiral wings for the purpose of slightly rotating the valves by the liquid flow for greater durability, as common in pump constructions, but it will be understood that this is not essential. The discharge chambers *e* of the three pumps are connected by passages *g*, and the end pump is connected by passage *h* to chamber *i*, having a port connected with the reservoir and normally closed by inwardly opening valve *k*, and from this chamber *i* the liquid pumped passes through a port controlled by a valve *l* to a chamber *m* with which low pressure pipe 11 connects. Chamber *m* also has a discharge port controlled by valve *n*, spring pressed by spring 2, preferably made adjustable as to pressure by screw abutment 3, as shown, this valve, when open, permitting the passage of liquid from chamber *m* to chamber *o* connected by passage *p* to chamber *q* connected with high pressure pipe 10. This chamber *q* has at the bottom a port connecting with the reservoir inside case F and controlled by inwardly opening valve *r*, and a safety discharge port 4 controlled by safety valve 5, on which bears lever 34 carrying adjustable weight 35 determining the pressure at which valve 5 will be raised to blow off liquid through port 4. Shaft 25 carries a cam 36 arranged to rock lever 34 when shaft 25 is rotated by hand, by contact of the cam with a bowl 6 on the lever. On further movement of the shaft 25 cam 36 engages bowl 6 on the upper portion of slide 37 to raise the latter, and by engagement of shoulders or arms 38 at the bottom of the slide with stems 7 on valves *k*, *r*, to raise

these valves for the passage of liquid from the chambers controlled thereby to the reservoir, valve *k* carrying at its top a stud 8 which engages and lifts valve *l*, thus permitting liquid to flow back to the reservoir through low pressure pipe 11, so that by thus raising valve stems 7, liquid is permitted to flow back to the reservoir from both the low pressure and high pressure cylinders A, C.

All the pump chambers, ports and passages are preferably formed in a solid block of metal by boring therethrough, as shown, the ends of the passages bored being stopped by suitable plugs. This is the preferred construction for high pressure, as usual in pumps, and it will be understood is not essential to the invention.

The operation of the construction is as follows:

Assuming that the parts are in the positions shown in the drawings, with lever 26 thrown over from the position shown in Fig. 2, to that shown in Fig. 3, so as to clutch shaft 20 to pulley 21 for driving the pumps, the pump plunger *a* first forces liquid through passages *g*, *h* and past valve *l* into low pressure pipe 11 and below the small or low pressure press plunger D, valve *k* being closed by the pressure in chamber *i* and valve *n* being closed by the pressure of spring 2. Plungers D, B are then raised by the pressure in cylinder C against the small plunger D, oil from the reservoir passing upward through valve *r* into chamber *q* and through pipe 10 to keep cylinder A full below press plunger B, vacuum in cylinder A being thus avoided. This operation of the press by small plunger D continues until the pressure is sufficient to open valve *n* against the adjusted pressure of spring 2, when the liquid passes also from chamber *m* into chamber *o* and through passage *p* and chamber *q* into high pressure pipe 10 and into cylinder A below high pressure plunger B, the press plunger then being forced up by pressure over its entire plunger surface as liquid passes to both cylinders A, C through pipes 10, 11. When the limit of pressure for which the weight 35 is adjusted is reached, valve 5 is raised against this weight, and the further increase of pressure is prevented by the blowing off of the liquid through port 4 into the reservoir.

When the pressing operation is completed, or at any other point where it is desired to hold the pressure fixed and the plunger stationary, lever 26 is moved from the position shown in Fig. 3 toward that shown in Fig. 2, thus releasing clutch 22 and stopping the pumps. The pressure and plungers are then maintained stationary as long as this position of the parts continues.

When the plungers are to be lowered, lever 26 is moved over farther, so as to move

- cam 36 to engage bowl 6 on lever 34 and rock the lever to raise weight 35 and thus permit relief valve 5 to be opened and relieve the pressure in the system, and then 5 the cam 36 on its further movement engages bowl 6' and raises slide 37 which, through arms 38 engaging stems 7 on valves *r*, *k* moves these valves upward, and through projection 8 on valve *k* also raises valve *l*, thus 10 opening both pipes 10, 11 to the reservoir and permitting the return of the liquid from cylinders A, C to the reservoir and the descent of the plungers B, D, the speed of this descent being controlled by the flow through 15 valves *r*, *k*, which in turn are controlled by the position of cam 36 operated by hand lever 26. On the full return of the press plungers, lever 26 is moved back to move the cam 36 into position to release slide 37 and lever 20 34 and permit them to return toward the position shown in Fig. 6, permitting valves *r*, *k*, *l*, to close for the next operation of the press, as above described, when the lever is thrown over to engage clutch 22. 25 It will be understood that the invention is not to be limited to the construction and arrangement of parts shown, but that many modifications may be made while still retaining the invention defined by the claims. 30 What I claim is:—
1. In a hydraulic press apparatus, the combination with low pressure and high pressure plungers, of pumping mechanism acting to force fluid against the low pressure plunger, a connection from the force passage of the pumping mechanism for delivering fluid against the high pressure plunger, a valve normally closing said connection and opened by the pressure of the fluid 35 pumped to supply fluid to the high pressure plunger through said connection when the pressure reaches a certain point, a pressure-operated relief valve for the system, and manually-operated means for stopping the 40 pumping mechanism and opening the relief valve to relieve the pressure in the system.
  2. In a hydraulic press apparatus, the combination with low pressure and high pressure plungers, of pumping mechanism 45 acting to force fluid against the low pressure plunger, a connection from the force passage of the pumping mechanism for delivering fluid against the high pressure plunger, a valve normally closing said connection and opened by the pressure of the fluid 50 pumped to supply fluid to the high pressure plunger through said connection when the pressure reaches a certain point, normally closed return valves on the force 55 passage of the pumping mechanism and on the connection for the high pressure plunger, a pressure-operated relief valve on the system, devices for opening said return valves on the force passage and high pressure 60 plunger connection to permit the es-

cape of the fluid for the return of the plungers, and a single manually-operated member acting to stop the pumping mechanism and open the relief valve to relieve the pressure in the system, and to operate said devices for the return of the plungers. 70

3. In a hydraulic press apparatus, the combination with the main plunger and its cylinder, of a small plunger carried by the main plunger, pressure fluid apparatus for supplying pressure fluid against the small plunger at the beginning of the plunger stroke and to the main plunger at a later point in the stroke, and an air connection for withdrawing air from the main plunger 75 cylinder. 80

4. In a hydraulic press apparatus, the combination with the main plunger and its cylinder, of a small plunger carried by the main plunger, pressure fluid apparatus for supplying pressure fluid against the small plunger at the beginning of the plunger stroke and to the main plunger at a later point in the stroke, an air connection for withdrawing air from the main plunger cylinder, and a liquid air seal between the main plunger and its cylinder wall. 85 90

5. The combination with the pump plunger *a* and its cylinder *b* and means for actuating said plunger, of force valve *l*, low pressure connection 11 beyond the force valve, pressure-operated valve *n*, high pressure connection 10 controlled by valve *n*, release valve *k* in line with valve *l*, release valve *r* on the high pressure connection, 95 manually-operated devices for opening valves *k*, *r* to permit the escape of fluid, and an extension on valve *k* engaging valve *l* to open the latter on the opening movement of valve *k*, driving mechanism for said pump, and manually-controlled shaft 25 operating to throw the driving mechanism out of operation to stop the pump and carrying cam 36 100 for operating the devices to open valves *k*, *r*. 105

6. The combination with the pump plunger *a* and its cylinder *b* and means for actuating said plunger, of force valve *l*, delivery connection 11 beyond the force valve, release valve *k* in line with valve *l*, manually-operated devices for opening valve *k* to permit the escape of fluid, an extension on valve *k* engaging valve *l* to open the latter on the opening movement of valve *k*, and manually-controlled shaft 25 operating to throw the driving mechanism out of operation 110 to stop the pump and carrying cam 36 for operating the devices to open valves *k*, *l*. 115

7. The combination with a hydraulic press plunger and pumping mechanism therefor, of a return valve, a pressure-operated relief valve, a manually-controlled member and connections for throwing the pumping mechanism out of operation to stop the supply of fluid, cam 36 carried by said member and devices operated by said cam for reliev- 120 125 130

ing the closing pressure on the relief valve and for opening said return valve for the return of the plunger.

8. The combination with a hydraulic press 5 plunger and pumping mechanism therefor, of a return valve, a pressure operated relief valve and a manually controlled member and connections for throwing the pumping mechanism into and out of operation, cam 10 36 carried by said member, and devices through which the cam operates to first relieve the closing pressure on the relief valve and then open said return valve for the return of the plunger on further movement of 15 the member after throwing the pumping mechanism out of operation, and first secures the closing of the return valve, then restores the closing pressure on the relief valve, and then throws the pumping mechanism into operation on the return movement of the manually operated member.
9. The combination with large and small 20 hydraulic press plungers and pumping mechanism therefor and a by-pass valve controlled by the pressure to apply the pressure first to the small plunger and then to the large plunger, of a return valve, a pressure operated relief valve and a manually 25 controlled member and connections for throwing the pumping mechanism into and out of operation, cam 36 carried by said member, and devices through which the cam operates to first relieve the closing pressure on the relief valve and then open said return valve for the return of the plunger on 30
- 35

further movement of the member after throwing the pumping mechanism out of operation, and first secures the closing of the return valve, then restores the closing pressure on the relief valve, and then throws the pumping mechanism into operation on the return movement of the manually operated member.

10. The combination with large and small 45 hydraulic press plungers and pumping mechanism therefor, by-pass valve *n* controlled by the pressure to apply the pressure first to the small plunger and then to the large plunger, force valve *l*, return valves *k*, *r*, and relief valve 5, of hand lever 26 and 50 connections for stopping and starting the pumping mechanism, cam 36 operated by said lever, and connections by which the movement of the lever in one direction successively stops the pumping mechanism, releases the closing pressure on the relief valve, opens the return valves *k*, *r*, valve *l* and by-pass valve *n*, and on the movement of the lever in the opposite direction successively secures the closing of valves *n*, *l*, *k*, 55 *r*, then restores the closing pressure on the relief valve, and then starts the pumping mechanism.

In testimony whereof, I have hereunto set my hand in the presence of two subscribing 65 witnesses.
